SHOETREE

Julius Gershune, Louisville, Ky.

Application April 3, 1933, Serial No. 664,221

11 Claims. (Cl. 12—128.1)

This invention relates to shoe trees, that is a device to be inserted in a shoe to prevent it from warping when not in use; to stretch the shoe and iron out any wrinkles that may have developed in same while wearing it; and thus prolong the fine appearance of the shoe and provide more comfort to the user of same.

The objects of the invention are, first, to provide a shoe tree, simple in construction, inexpensive to manufacture and convenient to use; second, to reduce the total number of parts, and to eliminate all catch or release springs commonly used on devices of this type; and third, to provide the shoe tree with simple means for easily adjusting it so that it may be used on various sizes of shoes.

Referring to the accompanying drawing which forms part of the following description;

Figure 1 is a vertical section of the shoe tree (shown in full lines) and an outline of a shoe (shown in dotted lines);

Figure 2, a plan view of the shoe tree;

Figure 3, a section on the line 3—3 of Figure 1;

Figure 4, a section on the line 4—4 of Figure 1;

Figure 5, a detail section on the line 5—5 of Figure 6;

Figure 6, a detail of member 2;

Figure 7, a partial side view showing details on line 7—7 of Figure 2;

Figure 8, a detail of member 3; and

Figure 9, an enlarged detail, illustrating the means provided in the shoe tree for adjusting it so that it may be used for shoes of various sizes.

The toe-body 1 preferably made of cast aluminum, contains a plurality of slotted holes 6 which extend more or less in a latitudinal direction, and in combination with same, two larger slots 7 are located in the extreme front portion of the toe body 1. These slots are for the purpose of economizing in material, and to provide the maximum amount of ventilation to the inner surface of the shoe with which the toe body 1 makes contact. The two slots 7 are made larger for the reason that the extreme front portion of shoes is commonly made of less pliable material, and will not easily lose its shape; therefore, this particular portion does not depend greatly on the toe body 1 to iron out any wrinkles or warped shape resulting from usual wear or other causes. With this combination of slotted holes arranged in the above described manner, the maximum amount of material is eliminated from the toe body 1 without sacrificing its effective contour or shape.

The underside of the toe body 1 at its rear end

is provided with a projection 8 which is preferably cast or formed integrally with said toe body. To the projection 8, is secured rigidly a shoulder rivet 5 which pivotally supports between its head 9 and the side of projection 8, the toggle arm 2 (see Figure 3).

A portion of the material on the rear end of the toe body 1 (to the right and left of projection 8) is eliminated so that it will be easy and convenient to secure the shoulder rivet 5 to projection 8. The remaining edge 10 (on the side of the toe body 1, shown in Figure 7) is curved in such a manner, so that the effective contour or shape embodying the extreme width and height of the toe body 1 is retained in said toe body 1.

The toggle arm 2 is provided with an elongated slot 11 with a series of slots 12 perpendicular or nearly so to said elongated slot 11 and acting as gateways leading into the pivot supporting slots 13. Said pivot supporting slots 13 are semicircular, or more or less so, and are offset to the sides of their respective gateway slots 12. On the toggle arm 3, thru hole 14, a shoulder rivet 4 is rigidly secured, and is adapted to move along the length of the elongated slot 11 thru any of the gateway slots 12 into a pivot supporting slot 13; where it may be seated (as shown in Figure 9), and thus pivotally support between its head 15 and the sides of member 3, the toggle arm 2 (see Figure 4). The foregoing arrangement enables one to vary the effective length of the toggle arm 2 as desired, and to hold the two toggle members in a pivotal and adjusted position; thereby, permitting the shoe tree to be used for various shoe lengths.

In using the shoe tree, the toe-body 1 is inserted inside the front end of the shoe; the heel piece 16 (preferably formed integrally with member 3 by bending to shape and twisting it, as shown in Figure 8) is placed against the inside of the rear end of the shoe; the pivot 4 is inserted in one of the pivot supporting slots 13 (selecting the one to suit the size of the shoe used); then the toggle arms 2 and 3 are pushed downwards (by means of pressure by hand exerted on either one or both of them), thus causing the shoe to stretch in a lengthwise direction; the natural resiliency of the shoe acting against the toe body 1 and heel body 16, will cause the pivot 4 to bear against and remain seated in the pivot supporting slot 13; and the downward movement of the toggle joint being limited by 17 (formed integrally with member 2 by bending a portion of its side thereof outward as shown in Figure 5).

in contact with edge 18 of member 3, will stop the movement of the toggle arms 2 and 3 when they have reached the position shown in Figure 1. In this position, pivot 4 is off center below the line of thrust, and the toggle members 2 and 3 will remain in their locked positions.

The foregoing is a description of a single specific embodiment of my invention which best illustrates it. However, there may be modifications in the construction of several parts and in the arrangement of same. For instance:

The toggle arm 3 integral with heel piece 16 may be a casting incorporating the same general idea as what is shown on the drawing.

15 The heel piece 16 may be made of wood and attached to the toggle arm 3 (a bar).

The toe body 1 may comprise a combination of two or more parts.

20 The slots 6 in the toe body 1 may extend in a latitudinal direction arranged in a staggered relationship; or said slots 6 may extend longitudinally; or said slots 6 may extend longitudinally arranged in a staggered relationship; or said slots 6 may extend obliquely; or said 25 slots 6 may extend obliquely arranged in a staggered relationship; or said slots 6 may comprise a combination of any two or more of these arrangements.

25 The pivots 4 and 5, instead of being riveted on to arm 3 and projection 8 respectively (see Figures 3 and 4), may have threaded portions for making these connections. Said threaded portions may be either conventional or drive screw threads. Either or a combination of these fastening means may be used.

30 Referring to Figure 1 and Figure 6, it will be seen that the elongated slot 11 extends downward obliquely relative to the front part of the toggle arm 2. Formed and arranged in this manner, better engagement may be had between the pivot 4 and the pivot supporting slots 13; and a finer or closer step by step adjustment in the direction of the shoe length is obtained thusly without decreasing the center distances between 35 slots 13. While this arrangement is preferred, it may be modified as follows:

35 First, the toggle arm 2 may be inverted so that the elongated slot 11 extends upward, obliquely relative to the front part of the toggle arm 2; and arranging differently the stop 17 and edge 18 to allow the toggle arms 2 and 3 to open and lock for making them operative in a shoe tree.

Second, the toggle arm 2 may be a rectangular bar (as indicated in Figure 9); the elongated slot 11 extending in said bar in a longitudinal direction; the stop 17 formed integrally with said bar by bending a section of its side thereof outward; and the toggle arm 3, a rectangular bar preferably formed integrally with the heel piece 16.

Third, in any of the above described arrangements, the elongated slot 11 together with slots 12 and 13 may be inverted in the toggle arm 2, and may extend in any desired direction.

45 Fourth, the gateway slots 12 may branch off obliquely to the elongated slot 11.

Fifth, the gateway slots 12 may extend in a curved direction from the elongated slot 11 into the pivot supporting slots 13.

50 Sixth, any or all corners in the slot arrangements described may be angular instead of rounded or circular.

75 Seventh, the elongated slot 11 together with slots 12 and 13 may be incorporated in the toggle arm 3 in any of the arrangements described

above; and pivot 4 secured to arm 2 (or secured to projection 8, eliminating member 2 entirely).

Eighth, the elongated slot 11 together with slots 12 and 13 may be incorporated in the projection 8 in any of the arrangements described above, thus 5 eliminating the toggle arm 2 entirely.

Ninth, the elongated slot 11 with slots 12 and 13 may be incorporated in the toe body proper; with a pivot engaging said slots and means connected to said pivot for compressing the toe body inside the front end of the shoe against the tension of same shoe.

Having thus described my invention and modifications of same, I claim:

1. In a device of the class described, a toe-body 15 including an integral projection; the sides of said projection being exposed for convenience in assembling said device; and means connected to said projection adjacent to one of said exposed sides for compressing said toe-body inside the 20 front end of a shoe.

2. In a device of the class described, a toe body having an integral projection extending from its underside; the sides of a portion of said projection being exposed for convenience in assembling said device; said projection being reinforced by an adjacent portion of said toe-body joining the top extremity of one of said exposed sides, and extending outwardly thereof; and means connected to said projection for compressing said toe-body 30 inside the front end of a shoe.

3. In a device of the class described, a toe body, a thrust body comprising a bar and a heel piece formed integrally by bending a portion of said bar endwise, forming an enclosed loop of 35 said portion and twisting said enclosed loop about the remaining portion of said bar, and means connecting said toe body and thrust body for compressing said members longitudinally relative each other against the tension inside of a shoe. 40

4. In a device of the class described, a toe body, a projection on said toe body, a pivot extending outwardly from one side of said projection, a head on said extending portion of said pivot fixed relative to said side, and means for compressing said toe body inside the front end of a shoe hinged on said pivot between said side and said head. 45

5. In a device of the class described, a toe body, and a thrust body consisting of a bar including an enclosed loop formed integrally at one end thereof; said enclosed loop being twisted about the remaining portion of said bar, the edge at the end of said loop bearing against the twist portion; and means connecting said toe body and thrust body 55 for compressing them longitudinally relative each other against the tension inside of a shoe.

6. A thrust body consisting of a bar including an enclosed loop formed integrally at one end thereof; said enclosed loop being twisted about the remaining portion of said bar, the edge at the end of said loop bearing against the twist portion. 60

7. A toggle joint consisting of a pair of toggle arms; a pivot extending outwardly from one side of one toggle arm and thru a slot included in the other toggle arm, and including a head on its extending portion fixed relative to said one side for the purpose of providing a fixed established clearance between the adjacent sides of said toggle arms; said other toggle arm being hinged on said pivot between said one side and said head; longitudinal adjustment between said toggle arms being provided by means of engagement 70 75

of said pivot in said slot; and means provided to hold said toggle arms in adjusted positions.

8. In a device of the class described, a toe body and a pair of toggle arms; one of said toggle arms pivotally connected at one end to said toe body; one of said toggle arms provided with an elongated slot for engagement with a pivot in the other toggle arm to provide longitudinal adjustment between said toggle arms; said toggle arm containing said slot provided with a bent portion, the bend line of which, extending longitudinally with respect to said slot; said toggle arm containing said pivot provided with an edge extending obliquely with respect to the center line of thrust of same toggle arm wherein it is contained; said edge adapted to abut said bent portion to lock said toggle arms in any one of their adjusted positions, the angle formed by their intersecting center lines of thrust being the same, when locked, for all of their adjusted positions; and means provided to hold said toggle arms in adjusted positions.

9. In a device of the class described, a toe body and a pair of toggle arms; one of said toggle arms pivotally connected at one end to said toe body; one of said toggle arms provided with an elongated slot extending obliquely with respect to the center line of thrust of same toggle arm wherein it is contained; the other toggle arm provided with a pivot for engagement with said slot to provide longitudinal adjustment between

said toggle arms; and means provided to hold said toggle arms in adjusted positions.

10. A toggle joint consisting of a pair of toggle arms; one of said toggle arms provided with an elongated slot for engagement with a pivot in the other toggle arm to obtain adjustment between said toggle arms; said toggle arm containing said slot provided with a bent portion, the bend line of which, extending longitudinally with respect to said slot; said toggle arm containing said pivot provided with an edge extending obliquely with respect to the center line of thrust of same toggle arm wherein it is contained; said edge adapted to abut said bent portion to lock said toggle arms in any one of their adjusted positions, the angle formed by their intersecting center lines of thrust being the same, when locked, for all of their adjusted positions; and means provided to hold said toggle arms in adjusted positions.

11. A toggle joint consisting of a pair of toggle arms; one of said toggle arms provided with an elongated slot extending obliquely with respect to the center line of thrust of same toggle arm wherein it is contained; the other toggle arm provided with a pivot for engagement with said slot to obtain adjustment between said toggle arms; and means provided to hold said toggle arms in adjusted positions.
